UNITED STATES PATENT OFFICE

PETER SWANSON, OF ELY, MINNESOTA

SWITCH TARGET

Application filed July 9, 1927. Serial No. 204,547.

This invention relates to switches and has special reference to a novel combination of switch stand target and operating means therefor.

The principal object of my present invention is to provide a safer and more positively acting target for switch stands.

Other objects and advantages of my invention will appear in the further description thereof.

Referring now to the accompanying drawings, forming part of this application, and wherein like reference characters indicate like parts:

Figure 1 is a broken perspective view of the upper end of a switch stand and staff having one of the improved targets or signalling devices attached thereto;

Figure 2 is an enlarged sectional view of the telescopic target operating rod;

Figure 3 is a perspective interior view of the operating lever lock;

Figure 4 is a transverse sectional view of the lock showing a portion of same in elevation; and

Figure 5 is a top plan view of the locking bolt.

1 represents the top of a common railroad switch stand which is of the type wherein the cap 2 of the stand is vertically reciprocable by the operating or throwing lever 3, so that when the switch is once thrown in either direction and the lever is in its closed position the position of the switch will be positively determined by the squared depending oblique portion 4 of the cap 2 entering the similarly shaped recess 5 in the head of the switch stand. Protruding laterally from the cap 2 is the lock carrying dog 6 which when the handle 3 is in closed position protrudes intermediate of the bifurcated arms 7 of the lever and the lock is usually attached through the hole in the dog 6 for preventing unauthorized movement of the lever.

This portion of the switch stand is in no wise changed for the installation of the invention which resides more particularly in the target, the flat body portion of which is indicated at 8 and which is made of any suitable thin metal having the large circular

bullseye 9 indicated upon both sides thereof. Upon either side of this body portion 8 is formed an arrow-like member 10 disposed at right angles to the body portion and the ends of these arrow-like members afford a pivotal connection for the target by the bolt or rod 11 passing therethrough and externally thereof, through the right angularly bent ends 12 of the supporting bar 13 which is secured to the switch staff 14 by a suitable U-shaped bolt 15 surrounding the same. Upon the uppermost corners of the heads of the arrow members 10 are angularly shaped projections 16 which when the target is in its uppermost position as shown in Figure 1 abut against the upper edge of the body portion of the cross bar 13 so as to positively define the upper position of the target. Upon the extreme upper or free end of the body portion of the target is formed an extension 17 having a hole therethrough carrying a red glass indicated at 18 so that when the target is in its uppermost position this glass covered hole will be presented directly in front of the clear light of the lantern 19, which is of the common variety, mounted upon the upper end of the switch staff 14, so that when the target is in this signalling position a red light will be displayed, providing, of course the switch light is in action.

To the lower substantially central body portion 8 of the target is pivotally attached as at 20 the target operating rod comprising the enlarged tubular member 21 into which the upper end of the rod 22 is inserted, after the insertion of the expansive helical spring 23 within the rod 21. Adjacent the upper end of the rod 22 is formed an elongated slot 24, and when the rod 22 is properly positioned within the tube 21 a holding bolt or pin 25 is installed through suitable holes in the tube 21, so that the two members are permanently telescoped, but yieldable in respect to their telescopic effect, they being movable in unison only after some considerable compression of the spring, so that when the lever 3 after being unlocked from the cap of the stand has been elevated only a portion of its entire travel the target will be completely elevated and on a further lifting of the lever 3 so as

to turn same in the throwing of the switch the spring 23 will have to yield in order to permit of such action, thus always insuring a complete danger signalling of the target whenever the lever of the switch has been materially elevated. If the switch is thrown, say for a siding, and the lever lowered to closed position, the target will assume a horizontal position, but with the arrows 10 which are painted red in direct horizontal position indicating that the switch is thrown for the siding. On the other hand, when the switch is thrown for clearance of the main line, the target appears in horizontal position but presenting an end view both of the arrows and the body portion to the main line, resulting in an all clear signal with the least appearance of the target possible, it being understood that the lower end of the rod 22 is pivotally connected as at 26 to the switch operating lever 3.

As an automatic locking means for the lever 3 I have provided the rectangularly shaped housing 27 mounted upon one of the bifurcations 7 of the lever, said housing carrying the locking bolt comprising the horizontal portion 28 rotatably mounted within the walls of the housing and the outwardly extending irregularly shaped portion 29 terminating in the finger 30 disposed at an angle to the portion 28, and which is designed to become engaged within the hole 31 within the lug 6 of the switch cap 2 when the lever is in its lowermost position.

The control of the locking bolt is accomplished as follows:

Pivottally mounted within the housing as at 32 is the L-shaped dog 33, the depending portion 34 of which is designed to drop by gravity, and, if desired, assisted by the expansive helical spring 35 which impinges against the upper covering of the housing 27, into the recess between the wall of the housing and the portion 28 of the locking bolt formed by the flattened or cutout portion 36 on the bolt, this action of the dog only occurring when the end 30 of the bolt is directly beneath the portion 28, that is, in its locked position as clearly shown in Figure 4 of the drawings. Beneath the dog 33 is the ordinary key hole indicated at 37 and into which a key may be thrust for raising the dog 33 out of such locking engagement intermediate of the bolt and the housing wall, which will permit of the bolt's being unlocked manually by the portion 29 being raised in relation to the portion 28, thus swinging the free end 30 from its locked position. When the bolt is in this latter or unlocked position the rotation of the portion 28 of the bolt brings into vertical alignment with the wall of the housing the flattened or cutout portion 38 and into which recess formed by such action is thrust the upwardly extending free end 39 of the dog 40 which is pivotally

mounted as at 41 and has formed integrally therewith the weighted end 42 which, by gravity, accomplishes its action and may be assisted in same by the use of any desired form of spring as indicated at 43. In this manner the locking bolt is retained in its unlocked position automatically until the switch handle 3 is thrust downwardly for engagement with the lug 6 of the switch stand 2, and when this occurs the position of the dog 40 is such as to result in the arcuately shaped weighted end 42 engaging the upstanding pin 44 carried by the lug 6 on the switch stand, and this engagement occurs just prior to the registering of the free end 30 of the locking bolt with the hole 31 in the lug and as such engagement will withdraw the upwardly extending end 39 of the dog 40 from its holding engagement with the portion 28 of the bolt the free end of the latter will drop either by gravity, spring action, or both, into its locked position with the lug 6. To produce such spring action I have shown the flat spring 45 as being carried vertically in the portion 28 of the bolt with its arcuately shaped end constantly bearing against the inner wall of the housing so that any rotating of the portion 28 of the bolt by an upward swinging or unlocking of the free end thereof will increase the action of said spring in an effort to return the bolt to normalcy.

As a means for limiting the throw of the portion 29 of the bolt the extreme edge 46 of the end of the housing is bent outwardly at an angle with a cutaway portion 47 therein through which the bent portion 29 of the bolt extends and is limited in either direction thereby.

As a preferred form of locking bolt construction I have shown the extreme end 30 which engages the hole 31 in the lug 6 of the switch stand as being disposed at an angle of approximately 80 degrees from the axis of the portion 28 as viewed in Figure 5 of the drawings, and I prefer to have the hole 31 in the lug 6 disposed at a similar angle so that any thrust or unintentional lift upon the switch handle will have a tendency to augment the holding stress of the locking bolt, and while I have illustrated the combination of automatic locking devices for the bolt it is evident that the simple locking bolt itself may be employed on a switch handle if desired, for example, on yard switches.

From the above it is apparent that I have devised an exceedingly simple and efficient switch signal or target and controlling means therefor, the automatic locking device acting as a secure means against incorrect signalling of the target, and the peculiar shape of the overhanging portion 29 of the locking bolt is such as to provide convenient means for raising same by hand.

From the foregoing it is evident that when

it is desired to throw the switch, assuming it to be in locked position, the key is inserted through the hole 37 and turned in clockwise direction, lifting the free end of the dog 33 from its locking position intermediate of the flattened portion 36 and wall of the housing 27, so that the bolt 28 may be readily rotated manually by grasping the protruding portion 29 of the bolt which will withdraw the portion 30 of said bolt from the hole 31 and permit the handle to be raised and the switch turned. When the bolt is in this unlocked position, the flattened portion 38 will be presented above the portion 39 of the dog 40 when it will automatically enter same either by the counterweight 42 on the opposite end of the dog 40 or the spring 43, or both, so that the locking bolt will be thus held in unlocked position until the switch handle is returned to its engagement with the lug 6 on the switch stand, and on doing so that rounded portion of the end 42 of the dog will engage the up-standing pin 44 and thus release the dog from its holding position in respect to the bolt 28 allowing the latter to freely rotate back to locked position with the terminus 30 of said bolt within the hole 31, in which position the free end of the dog 33 will again drop into the space provided by the cutaway portion 36 when the key is removed.

Having thus described my invention, what I claim and desire to secure by Letters Patent, is:

1. An automatic catch for switch levers comprising a housing carried by the lever, a rotatable engaging bolt carried in the housing, and means for automatically locking the bolt in either engaged or disengaged position.
2. The combination with a railroad switch stand having a projecting lug with a hole therein for cooperative engagement with a switch throwing lever, of an automatic catch for said lever comprising a housing carried by the lever, a rotatable locking bolt mounted within the housing and having a free hook-like locking terminus whereby any lifting stress on the lever prior to the unhooking of the catch will augment the holding action of same.
3. A switch lever lock of the type described comprising a housing carried by the lever, a bolt one end of which is rotatably mounted within the housing and the opposite end made swingable in respect thereto with the terminus of the swingable end disposed at substantially an 80 degree angle to the axial line of the rotatable portion for the purpose described.
4. An automatic switch lever catch for a switch stand having a lug with a hole disposed obliquely therethrough, said catch being disposed at such an angle to register with said hole as to augment its holding engage-

ment therein when the lever is raised without the catch being released.

5. A switch lever catch of the type described comprising a housing carried by the lever, a bolt having one end rotatably mounted within the housing, and the other end swingable outwardly of the housing, the portion adjacent the extreme free end being employed as a handle for manipulating the bolt, and means for automatically locking the bolt in either engaged or disengaged position.

In testimony whereof I affix my signature.

PETER SWANSON.
